UNITED STATES PATENT OFFICE.

CHARLES M. H. LEIGHTON, OF MILFORD, NEW HAMPSHIRE, ASSIGNOR TO DRAPER CORPORATION, OF HOPEDALE, MASSACHUSETTS, A CORPORATION OF MAINE.

SELVAGE GUARD FOR LOOMS.

Application filed November 30, 1921. Serial No. 518,946.

To all whom it may concern:

Be it known that I, CHARLES M. H. LEIGHTON, a citizen of the United States, and resident of Milford, county of Hillsborough, 5 State of New Hampshire, have invented an Improvement in Selvage Guards for Looms, of which the following description, in connection with the accompanying drawing, is a specification, like characters on the drawing representing like parts.

This invention relates to selvage guards for looms and has for its object to provide a simple, efficient and practical device and one which may readily be attached to existing loom structures.

The invention has for its object to provide means for insuring the formation of an even regular and straight selvage which is frequently difficult to secure especially with certain classes of warp and filling, although the device is adapted for use with any type of warp and filling and may be utilized whenever found necessary.

In the weaving, for example, of padding material for garments wherein it is common to employ cotton warp and jute filling great difficulty has heretofore been experienced in producing a straight, regular and perfect selvage. Jute filling is a rather coarse yarn 20 and is more or less rough because of knots, bunches or other irregularities. This interferes with the unwinding of the filling and produces a tension on the running filling sufficient to pull the selvage out of line. 25 Any irregularity or jog in the selvage is objectionable not only to the manufacturers of clothing using the padding but because it interferes with the proper finishing of the padding. In the finishing operation, the 30 fabric is subjected to heavy pressure in a mangle and when the selvage is irregular the fabric is frequently rolled back or doubled along the selvage and sometimes cut or damaged.

45 The present invention insures that the selvage shall have the same thickness, the same tension and elasticity, and shall be even and regular throughout.

The invention in its preferred form comprises a device mounted upon the usual temple which has a movement rearward and forward of the loom frame and this movement is utilized to secure the operation of the selvage guard.

55 An important feature of the invention

resides in the control of the movement of the selvage guard by the cloth itself so that the guard is withdrawn out of the way after it has performed its function and so as not to interfere with the lay or other moving 60 part of the loom upon the beat-up.

These and other objects and features of the invention will appear more fully from the accompanying description and drawing and will be particularly pointed out in the 65 claims.

The drawings disclose a preferred form of the invention in connection with an ordinary form of temple only those parts directly connected with the invention being 70 illustrated.

In the drawings;

Fig. 1 is a plan view of a portion of the loom and of the cloth and warp adjacent the fell at one side, disclosing a preferred embodiment of the invention;

Fig. 2 is a side elevation of the construction shown in Fig. 1;

Fig. 3 is a detail in front elevation of the construction added to the usual temple and 80 shown in Fig. 1 as embodying the invention;

Figs. 4, 5 and 6 are somewhat diagrammatic views in perspective showing the different positions of the arm and fingers of the device embodying the invention with relation to the fell, selvage and cloth.

As the invention is applicable to any type of loom wherein there is a frame, a lay, shed forming mechanism, a shuttle and shuttle picking mechanism, and other usual instrumentalities it is unnecessary to illustrate such features which are familiar to those skilled in the art.

A common form of temple is, however, illustrated because this is utilized as the support for the features embodying this invention. As the construction is generally similar at both sides of the loom it is sufficient only to refer to that at one side.

The temple stand 1 is secured by screws 100 2 to the loom frame forward of the fell. The shank 3 of the temple has a rearward and forward sliding movement in the stand 1 and carries at its rearward end the temple head 4. A heel 5 depends from the temple head and is struck by the lay on the beat-up to move the temple forwardly all in a well known manner.

The sheet of warps 6 extends through the shed forming mechanism forwardly to the 110

breast beam and the fell 7 of the cloth extends normally directly in the rear of the temple when in its rearward position as shown in Figure 1.

5 In the preferred construction of the invention illustrated a bracket 8 shown as an angular plate is secured to the top of the temple head and this may be effected, as illustrated, by means of the usual screw 9 and nut 10 employed in locking the cap and pod of the temple together. The depending leg 11 of the bracket 8 is located inwardly away from the temple head and in this leg 11 is rigidly mounted a horizontal 15 stud which thus extends laterally from the temple. This stud is provided with a head 13, with a shoulder 14 abutting the leg 11 and with a threaded reduced portion 15 carrying a nut 16 by which the stud is locked 20 in place.

An arm in the form of a flat metal plate 17 is pivotally mounted or journalled on the stud 12, being for that purpose bent to embrace the stud. Preferably the plate 17 is 25 bifurcated at its forward end and between the bifurcations a helical spring 18 is mounted on the stud 12 with one end engaging the plate 17 and the other end engaging the temple head so that this spring acts normally to 30 depress the rear end of the plate.

The plate 17 at its rear edge is provided with an outer finger 19 and an inner finger 20. These fingers are preferably formed from the metal of the plate itself being bent 35 at right angles thereto and are provided with smooth round lower ends.

The construction and proportions are such that when the temple is in its normal rearward position as shown in Figs. 1 and 2 the 40 outer finger 19 is positioned rearward of the fell and adjacent the selvage and so as to extend transversely across the plane of the cloth. Preferably, as shown, the finger extends immediately inside of the selvage warp 45 or warps through the shed. With the device in this position the inner finger 20 extends through the shed and rearward of the fell.

When the beat up takes place and the lay 50 strikes the heel 5 of the temple carrying the temple forwardly the inner finger 20 rides up over the fell onto the cloth and thus the engagement of the fell of the cloth with the finger 20 acts to raise the plate 17 and consequently the outer finger 19 and to withdraw the outer finger and carry it out of the way before the filling is beaten in.

Thus the device is under the control of the cloth and the withdrawing action is certain whatever may be the exact position of the outer finger 19 laterally with respect to the selvage.

The operation of the device is now apparent and is illustrated in Figures 4, 5 and 6. 65 In Figure 4 the plate 17 and the fingers 19

and 20 are shown in normal position extending down through the sheet of warp immediately in rear of the filling and a pick of filling 21 has just been made to the near side of the loom. In Figure 5 the pick 21 has just been beaten in and it will be noted that the plate 17 has moved forwardly and that the inner finger 20 riding up over the fell onto the cloth has lifted the outer finger 19 and withdrawn it out of the way. As the lay retreats and the temple moves rearwardly the plate 17 and fingers 20 and 19 again assume the original position as shown in Figure 6. As the shuttle is now picked to the opposite side of the loom the pick 22 of filling is carried around the outer finger 19 as shown in Figure 6 so that the strain on the selvage is relieved because the finger 19 holds the filling firmly at the selvage. The finger also provides a little looseness in the filling when the pick is beaten in there. There is thus no danger of any unevenness of construction or tension resulting at the selvage. As the lay moves forwardly to beat in the pick 22 the plate 17 is again raised through the action of the inner finger 20 engaging the fell 21 and the finger 19 is withdrawn out of the way.

It will thus be seen that there is provided a very simple and efficient construction 95 which may readily be adapted to existing looms and which positively and uniformly guards the selvage and insures the required results.

Having thus described my invention what 100 I claim as new and desire to secure by Letters Patent is:

1. In a loom comprising a frame, a lay, 105 shed forming mechanism, a shuttle and shuttle picking mechanism, and a temple mounted for forward and rearward movement on the frame with the forward movement taking place on the beat-up, an arm pivotally supported on a horizontal axis from the temple and provided with downwardly projecting inner and outer fingers, the arm when depressed with the temple in rearward position acting to position the outer finger rearward of the fell adjacent the selvage and extending transversely across the plane of the cloth and acting to position the inner finger through the shed rearward of the fell whereby on the pick of the shuttle to the opposite side the filling is drawn around the outer finger relieving the strain on the selvage warp, the inner finger upon the beat-up and forward movement of the temple riding up over the fell onto the cloth and acting to raise the arm and withdraw the outer finger before the said pick of filling is beaten in.

2. In a loom comprising a frame, a lay, 115 shed forming mechanism, a shuttle and shuttle picking mechanism, a finger movably mounted from the frame and acting to as-

sume a position adjacent the fell and the selvage prior to the pick of the shuttle toward the opposite side whereby the filling is drawn around the finger and the strain on the selvage warp relieved and means acting by engagement with the cloth to withdraw the finger from the filling before the said pick is beaten in.

3. In a loom comprising a frame, a lay, 10 shed forming mechanism, a shuttle and shuttle picking mechanism, a finger movably mounted from the frame, and means to move the finger into a position rearward of the fell, adjacent the selvage and extending transversely across the plane of the cloth 15 prior to the pick of the shuttle to the opposite side whereby the filling is drawn around the finger relieving the strain on the selvage warp and means acting by engagement with 20 the cloth to withdraw the finger from the said position before the said pick of filling is beaten in.

4. In a loom comprising a frame, a lay, 25 shed forming mechanism, a shuttle and shuttle picking mechanism, and a temple mount-

ed for forward and rearward movement on the frame with the forward movement taking place on the beat-up, a stud extending laterally from the temple, a plate journaled on the stud and provided with downwardly projecting inner and outer fingers, means acting normally to depress the plate, the plate when depressed with the temple in rearward position acting to position the outer finger rearward of the fell, adjacent 30 the selvage and extending transversely across the plane of the cloth and acting to position the inner finger through the shed rearward of the fell whereby on the pick of the shuttle to the opposite side the filling is drawn around the outer finger relieving the strain on the selvage warp, the inner finger upon the beat-up and forward movement of the temple riding up over the fell onto the cloth and acting to raise the arm and withdraw the outer finger before the said pick of filling is beaten in.

In testimony whereof, I have signed my name to this specification.

CHARLES M. H. LEIGHTON.
